[57] CLAIM

The ornamental design for a concourse seal, substantially as shown and described.

DESCRIPTION

FIG. 1 is a fragmentary, elongated perspective view of a concourse seal, showing my new design;

FIG. 2 is a fragmentary, top plan view thereof;

FIG. 3 is a fragmentary, side elevational view thereof;

FIG. 4 is a fragmentary, bottom view thereof;

FIG. 5 is a transverse, cross sectional view of a concourse seal similar to that shown in FIG. 1 but having a greater transverse dimension;

FIG. 6 is a fragmentary, top plan view of my design as set forth in FIG. 5; and

FIG. 7 is a fragmentary, bottom view of my design as set forth in FIG. 5.

The seal has been disclosed in fragmentary form in the several views to indicate an article of indefinite length.
